US00D881125S

(12) **United States Design Patent** (10) **Patent No.:** **US D881,125 S**
(45) **Date of Patent:** **** Apr. 14, 2020**

(54) **GAME CONTROLLER MOTOR SET**

(71) Applicant: **Ironburg Inventions Limited**,
Wincanton, Somerset (GB)

(72) Inventors: **Duncan Ironmonger**, Suwanee, GA
(US); **Carl Jeffrey**, Gloucestershire
(GB); **Michael Parker**, Gloucestershire
(GB)

(73) Assignee: **Ironburg Inventions Limited**,
Wincanton (GB)

(**) Term: **15 Years**

(21) Appl. No.: **29/662,379**

(22) Filed: **Sep. 5, 2018**

(51) LOC (12) Cl. **13-01**

(52) U.S. Cl.

USPC **D13/112; D21/333**

(58) **Field of Classification Search**

CLAIM

The ornamental design for a game controller motor set, as
shown and described.

DESCRIPTION

FIG. 1 is a front and top perspective view of a game
controller motor set in accordance with the present design;
FIG. 2 is a front and bottom perspective view of the game
controller motor set of FIG. 1;

FIG. 3 is a front view of the game controller motor set of
FIG. 1;

FIG. 4 is a rear view of the games controller motor set of
FIG. 1;

FIG. 5 is a right side view of the game controller motor set
of FIG. 1;

FIG. 6 is a left side view of the game controller motor set of
FIG. 1;

FIG. 7 is a top side view of the game controller motor set of
FIG. 1; and,

FIG. 8 is a bottom view of the game controller motor set of
FIG. 1.

Any broken lines in the drawings show environment that
forms no part of the claimed design.

1 Claim, 7 Drawing Sheets
